UNITED STATES PATENT OFFICE.

JAMES A. CAMERON AND GUSTAF BIRGER BIRCH, OF BROOKLYN, NEW YORK, ASSIGNEES TO CAMERON MACHINE COMPANY, OF BROOKLYN, NEW YORK, A CORPORATION OF NEW YORK.

SLITTING DEVICE.

Application filed March 19, 1919. Serial No. 283,497.

To all whom it may concern:

Be it known that we, JAMES A. CAMERON and GUSTAF B. BIRCH, citizens of the United States, and residents of the borough of Brooklyn, in the city of New York, county of Kings, and State of New York, have invented certain new and useful Improvements in Slitting Devices, of which the following is a specification.

10 The present invention relates generally to slitting devices such as are used for dividing a web of flexible material into sections. In devices of this character there is usually employed a cutter roll against which bears 15 one or more cutting members, the cutter roll being of material harder than that of the cutting member which is of the character commonly known as a score cutter, the cutting edge of which is relatively blunt. It 20 is customary to drive the cutter roll, the score cutter, under pressure, bearing against it and rotating idly in engagement with it.

The main object of this invention is to prevent the score cutter from "wobbling" 25 during the cutting action. This is accomplished by arranging the cutter on a pivotal support so that it has, with respect to the direction of rotation of the cutter roll, a "trailing" movement.

30 Another feature of the invention resides in a construction whereby the cutter structure may be adjusted, as a unit, lengthwise of the cutter roll without disturbing the adjustment of the spring that holds it 35 against the cutter roll.

Other features of construction will appear as the specification proceeds:—

Figure 1 is a side elevation of a device 40 embodying the invention, partly in section and with elements broken away.

Figure 2 is a view of the device shown in Fig. 1 looking in the direction of arrow 2 and partly in section.

The cutter roll 1 comprises an inner core 45 2 and an outer shell 3 that may, as shown, consist of several sleeve portions. This cutter roll is suitably driven as by means of pulley 4 or otherwise. Adjacent the cutter roll is a rocking support 5 provided with a dovetail portion 6 which presents a flat surface as shown in Fig. 2. The cutting member 7 consists here of a bracket 8 slidably supported upon the dovetail portion 6 and

secured in position by means of a set screw 9. This bracket 8 is provided with bearings 55 10 into which extend pivots 11 of a cutter holder 12 having a bifurcated portion 13 in which a score cutter 14 is rotatably mounted. The bracket 8 is also provided with a tail portion 15 which forms an abutment member for a spring 16 that extends 60 from the end of cutter holder 12, where it is secured by a screw 17, to the screw 18 engaging with the outer end of said tail portion 15. The rocking support 5 is 65 provided with a handle 19 and carries on its circumference a ratchet 20. 21 is a detent carried by an arm 22 pivotally supported at 23. This detent is normally in engagement with said ratchet by reason of 70 a counter-weight 24 and the ratchet and detent are released by the depression of a treadle 25 that forms part of arm 22.

It will be seen that when rocking member 5 is turned to the right in Fig. 1, score cutter 75 14 will be brought into engagement with cutter roll 1; and that after contact has been made between score cutter 14 and cutter roll 1 continued movement to the right (Fig. 1) of the rocking member will cause cutter holder 80 12 to turn in bearing 10 so that the rocking member may continue its movement toward the cutter roll. This turning movement on center 11 will increase the tension of spring 16. It will be understood that, owing to the 85 fact that tail portion 15, which acts as an abutment for spring 16, is adjustable with bracket 8; that the cutter may be adjusted, as a unit, lengthwise of cutter roll 1; and that no parts, except the set screw 9 need be disconnected. This is a material improvement 90 over structures in which the abutment member is independent of the cutting unit because in cases of that character the spring must be disconnected from the abutment 95 member when an adjustment of the cutter is to be made.

It will further be seen that the parts are so arranged that if a radial line were to be drawn between the centers of the cutter roll 100 1 and pivotal support 10 such a line would be in advance, with respect to the direction of rotation of cutter roll 1, of a similar line drawn between the center of cutter roll 1 and the center of rotation 26 of the score 105 cutter. The result is that the score cutter

has what may be called a "trailing" movement with respect to cutter roll 1, the effect of which is to counteract any tendency on the part of score cutter 14 to "wobble". This is of the utmost importance in preventing slight inaccuracies in slitting due to minute variations in the parts; and it will be understood that if the arrangement were reversed, the line between the center of roll 1 and the pivotal support 10 would be behind the line between the center of 1 and the pivotal center 26 and no "trailing" action would take place. Consequently, any tendency of the score cutter to "wobble" would be increased rather than reduced. The function of detent 21 is to hold the parts in the position to which they have been adjusted.

We claim:

20 A slitting device comprising: a cutter roll, a rocking support in front of and below said

cutter roll and having its axis parallel to the cutter roll, a bracket adjustable on said rocking support in a direction parallel to the axis of the cutter roll, a cutter holder supported on a pivot carried by the bracket parallel 25 to the cutter roll, a score cutter engaging said cutter roll and rotatably mounted on the cutter holder, a tail portion, on the bracket, extending outwardly and downwardly away from the cutter roll, and a spring interposed 30 between the cutter holder and the tail portion, said spring extending substantially in the direction of said tail portion, and means for directly placing said spring under tension.

Signed at the borough of Brooklyn, in the county of Kings, city and State of New York, this 11th day of March, 1919.

JAMES A. CAMERON.
GUSTAF BIRGER BIRCH.
